US0D1006026S

(12) **United States Design Patent** (10) **Patent No.:** **US D1,006,026 S**
(45) **Date of Patent:** **** Nov. 28, 2023**

(54) **CASE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iulius**, San Francisco, CA (US); **M. Evans**, San Francisco, CA (US); **Hankey**, San Francisco, CA (US); **Julian Hoenig**, San Francisco, CA (US); **Richard P. Howarth**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/740,577**

(22) Filed: **Jul. 6, 2020**

Related U.S. Application Data

(63) Continuation of application No. 29/645,886, filed on Apr. 30, 2018, now Pat. No. Des. 889,474, which is a continuation of application No. 29/534,235, filed on Jul. 27, 2015, now Pat. No. Des. 816,677, which is a continuation of application No. 29/470,472, filed on Oct. 22, 2013, now Pat. No. Des. 735,205.

CLAIM

The ornamental design for a case, as shown and described.

DESCRIPTION

FIG. 1 is a bottom front perspective view of a case showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 in FIG. 2;

FIG. 9 is a bottom front perspective view of another embodiment of a case showing the claimed design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a cross-sectional view taken along line 16-16 in FIG. 10.

The dashed broken lines in the figures show portions of the case that form no part of the claimed design.

The dot-dash broken lines in the figures and the areas within the dot-dash broken lines show portions of the case that form no part of the claimed design.

The cross-hatched shading in FIGS. 8 and 16 forms no part of the claimed design.
